CLAIM

The ornamental design for a light clip, as shown and described.

DESCRIPTION

FIG. 1 is a perspective view of a light clip showing my new design;

FIG. 2 is another perspective view thereof;

FIG. 3 is a front elevational view thereof; the rear elevational view being a mirror image of FIG. 3;

FIG. 4 is a left elevational view thereof;

FIG. 5 is a right side view thereof;

FIG. 6 is a top side view thereof; and,

FIG. 7 is a bottom plan view thereof.

The broken lines in the figures are for the purposes of illustrating portions of the light clip, which form no part of the claimed design.

1 Claim, 6 Drawing Sheets
